UNITED STATES PATENT OFFICE.

JAMES MORAN AND LUTHER H. GRIFFITH, OF SEATTLE, WASHINGTON.

TUNNEL-BORING APPARATUS.

No. 825,857.

Specification of Letters Patent.

Patented July 10, 1906.

Application filed February 10, 1906. Serial No 300,417.

To all whom it may concern.

Be it known that we, JAMES MORAN and LUTHER H. GRIFFITH, citizens of the United States, residing at Seattle, in the county of King and State of Washington, have invented certain new and useful Improvements in Tunnel-Boring Apparatus, of which the following is a specification, reference being had therein to the accompanying drawings, in which—

Figure 1 is a longitudinal vertical section of an embodiment of our invention; Fig. 2, a horizontal section; Fig. 3, an end elevation; Fig. 4, a fragmentary cross-sectional view; 15 and Fig. 5 perspective views of the preferred form of cutter-knives.

This invention relates to mechanically-operated earth-borers; and its object is to provide apparatus which is capable of doing tunnel-work or the like with considerable speed and at a relatively low cost.

The invention consists of the devices for excavating and for transmuting the cuttings to the dumping-ground outside of the tunnel.

25 In the said drawings the reference-numeral 10 designates a truck-frame having at the front car-wheels of the ordinary type and at the rear wheels without flanges, thus allowing of their being slid laterally of the track-30 rails to adjust the truck and the boring apparatus thereon in a horizontal direction.

The swerving of the truck is attained by any suitable means, such as screws 14, passing through nut-sleeves 15, secured to the 35 truck or to the casing or framework 16 thereabove. The points of the screws are desirably seated in socket-plates 14' to afford increased bearings against the adjacent walls 17 of the tunnel. By withdrawing one of 40 these screws and moving the opposite one outwardly it is apparent that the truck will be correspondingly swerved. These screws, together with similar ones 18 at the front end 45 of truck, likewise serve to secure the latter against endwise movement upon the rails and hold the same rigid while the boring is being done.

Vertical angular adjustment is given to the truck by raising or lowering its rear end relatively of the axle 12 by means of adjustment-screws 19, (see Figs. 1 and 4,) operating through fixed nuts 20 and impinging against respective top journal-brasses 21, which are 55 slideable in housings 22. Rotatable and movable axially in journal-boxes 23 of the truck is a longitudinally-disposed shaft 24 of

greater length than the truck and provided with a keyway 25. Carried at the forward end of this shaft is a cutter-head 26, provided with a plurality of radial arms 26', 60 having along one of their respective edges diagonally-arranged flanges or deflector-plates 26'', whereby the excavated material is caused to be moved rearwardly to fall into the mouth of the conduit 27. The excavating is accomplished by cutter-points 28, which protrude diagonally forward from the opposite edges of the said arms to the flanges thereof and are detachably secured in place by bolts 29 or their equivalent. While these 70 points may be formed in a variety of shapes, those illustrated in Fig. 5 show an advantageous construction and of which the upper one is shown with a rectangular scraping or cutting edge A; the other with an acute cutting edge B, and in practice these two types 75 of points are desirably placed upon alternate arms of the head, as represented in Fig. 3.

In axial alinement with the head 26 and protruding forwardly therefrom is an earth-auger 30, inclosed by a tubular case 31, having in proximity of the head apertures 31', wherethrough the borings from the auger are discharged. The purpose of this case is to furnish an additional bearing for the said rotary parts and serves in retaining the cutter-head in its proper direction, even though the latter has been so advanced as to be at a considerable distance from the foremost of the boxes 23.

The shaft 24 is driven through the medium of power-transmission gearing from a motor 32 or, where the duty is excessive, by two or more such units, and such gearing may advantageously comprise a pinion 32' on the 95 armature-shaft, meshing with a spur-wheel 33 upon the transverse spindle 34, having screw-threads cut therein which engage with the worm-wheels 35 on the longitudinal shafts 36, provided with pinions 37, meshing 100 with the internally-disposed teeth of the wheel 38, which is splined to the boring-shaft 24.

The motor-shaft is also operatively connected to a shaft 39 by an endless belt 40, 105 passing around pulleys 41 and 42 upon the respective shafts. The last-named shaft is mounted in an eccentric box 43, which is actuated by a hand-lever 44, whereby the wheel 45, carried by the shaft, is controlled to 110 put the same into or out of frictional engagement with the wheel 46 upon the shaft 47,

This shaft has fixedly mounted thereon a drum or drums 48, about which are coiled the lines 49 49', extending from straps 50 and 50', which are respectively connected by trunnions 51 to the shaft 24 to the rear and in front of the drums. The purpose of these lines and the mechanism for winding the same is to draw the shaft forwardly to present the cutter-head to the work or for receding the same therefrom when required to readjust the position of the truck, and by pivotally connecting the said straps to the shaft the strains between the lines are equalized or imparted in an axial direction to the shaft. In certain classes of digging, however, the power of the above-described cutter-feeding devices is insufficient to exert the necessary forward pressure to give ample feed motion to the cutters for doing efficient work. Then resort is had to the supplementary feed apparatus, which is clearly illustrated in Fig. 1. This feed apparatus consists of a hydraulic cylinder 55, mounted upon car-wheels 56 and having a piston 57, with its rod 57' extending forwardly through stuffing-box 58. The action of the piston is attained by the pressure of fluid which is admitted or withdrawn, as required, through the passages 59, leading to the ends of the cylinder from the valve-chamber 60, communicatively connected with the source of water-supply and controlled by a valve 61, which is operated by the lever 61' and rod 62, extending to within easy reach of the attendant. Provided at the forward end of the rod 57' are hooked members 63, openable upon pins 64 of a strap 65, recessed into an annular groove of the rod. The hooks 63' of these members are adapted to grapple the shaft 24 over the end enlargement 24' of the same and is detachably held in such engagement by a link 66, which encircles the hooked arms, or when they are to be held in a distended position by being moved to encircle the flaring tail-arms 63".

The conduit 27, as aforesaid, has its mouth in close proximity of the cutter-head and is connected to the boss 26" of the same by a suspending rod 68, passing about the peripheral groove of a ring 69, loosely mounted in the said boss. The conduit has the top of its front end cut away and the remainder flared, as at 70, to provide a pan to receive the droppings from the cutter-points. The front section or sections of the conduit pipes makes telescopic connection with the section 27' next behind, and this section with the others, forming the ground-line, are connected in any suitable way, as by joints 72. This conduit leads from where the material is dug to the point of delivery, and the excavated material is conveyed through the conduit by and with a stream of water, which is jettied into the same from supply-pipes 73 and de-sirably through terminal reverse bends 74.

The operation of our invention will, it is thought, be understood from the foregoing. By using the two illustrated types of cutting-knives the work is especially expedited, the pointed-ended ones scoring the face, while the chisel-like blades remove the corrugations thus made. Should a strata of rock or a big boulder appear in the path of the machine, the work of the latter would be discontinued until such obstruction is removed, being first broken into fragments capable of being handled conveniently and passed lengthwise through the machine.

Having described our invention, what we claim as new, and desire to secure by Letters Patent, is—

1. In a tunnel-boring apparatus, the combination of the truck, a shaft, a cutter-head carried by the shaft detachable cutter-points for said head, means to rotate said shaft, means to impart a longitudinal movement to the shaft relatively of the truck, and a conduit wherethrough the excavations are removed by the agency of water.

2. In a tunnel-boring apparatus, the combination of the truck, a shaft, a cutter-head carried by the shaft detachable cutter-points for said head, means to rotate said shaft, means to impart a longitudinal movement to the shaft relatively of the truck, supplemental means including a hydraulic cylinder for exerting an end pressure or pull upon the shaft, and a conduit wherethrough the excavations are removed by the agency of water.

3. In a tunnel-boring apparatus, the combination with the truck, the supporting-track, and the power-motor, of a shaft, the driving connections between the motor and the shaft, boring devices mounted upon the shaft, and means actuated by said motor whereby the shaft may be predeterminedly moved in either direction longitudinally of the truck.

4. In tunnel-boring apparatus, the combination of the truck, the rotatable shaft mounted upon the truck, means to drive said shaft, means to move said shaft longitudinally in its bearings, a cutter-head provided with flanged arms rigidly secured to the said shaft, cutter-points detachably connected to said arms of the cutter-head, a conduit provided with a telescopic forward portion the advanced end of which is flared transversely, and a water-pipe having its discharge end directed into said conduit.

5. In tunnel-boring apparatus, the combination of the truck, the rotatable shaft mounted upon the truck, means to drive said shaft, means to move said shaft longitudinally in its bearings, a cutter-head provided with flanged arms rigidly secured to the said shaft, cutter-points detachably connected to said arms of the cutter-head, a conduit provided with a telescopic forward portion the advanced end of which is flared transversely

and connected by a support to a grooved ring rotatably mounted on the hub of said head, said ring, and a water-pipe having its discharge end directed into said conduit.

5. 6. In tunnel-boring apparatus, the combination of the truck, the rotatable shaft mounted upon the truck, means to drive said shaft, means to move said shaft longitudinally in its bearings, a cutter-head provided with flanged arms rigidly secured to the said shaft, an auger arranged axially of the shaft 25 and protruding forwardly of the said head, a casing for the auger, cutter-points detachably connected to said arms of the cutter-head, a conduit provided with a telescopic forward portion the advanced end of which 30 is flared transversely and connected by a support to a grooved ring rotatably mounted on the hub of said head, said ring, and a water-pipe having its discharge end directed into said conduit.
10. 7. In tunnel-boring apparatus, the combination of the truck, the rotatable shaft mounted upon the truck, means to drive said
15. 8. In tunnel-boring apparatus, the combination of the truck, the rotatable shaft mounted upon the truck, means to drive said
20. 9. In tunnel-boring apparatus, the combination of the truck, the rotatable shaft mounted upon the truck, means to drive said

shaft, means to move said shaft longitudinally in its bearings, a cutter-head provided with flanged arms rigidly secured to the said shaft, an auger arranged axially of the shaft 25 and protruding forwardly of the said head, a casing for the auger, cutter-points detachably connected to said arms of the cutter-head, a conduit provided with a telescopic forward portion the advanced end of which 30 is flared transversely and connected by a support to a grooved ring rotatably mounted on the hub of said head, said ring, and a water-pipe having its discharge end directed into said conduit.

In testimony whereof we affix our signatures in presence of two witnesses.
